COMBINED WALLET AND PURSE

Samuel Plotzky, Brooklyn, N. Y.

Application June 14, 1944, Serial No. 540,226

2 Claims. (CL. 150—35)

1

This invention relates to new and useful improvements in a wallet.

More specifically, the invention proposes the construction of a wallet characterized by having a "zipper" coin pocket, a billfold on one side thereof and another fold on the opposite side thereof having two compartments for receiving cards, licenses and other papers, each of the folds having snap fasteners for holding them closed.

It is further proposed to provide a wallet as aforesaid in which only the "zipper" coin pocket and billfold are provided.

A further object is to provide either of the aforesaid wallets constructed in a new manner providing simple construction and greater strength and wearability.

A further object is to provide a wallet of either of the aforesaid types in which the coin pocket has two end walls and is closed by a slide fastener extending along two sides of the coin pocket at right angles to each other.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a wallet constructed in accordance with this invention.

Fig. 2 is a perspective view of the wallet taken from the other side, with the folds and coin pocket open.

Fig. 3 is a front view of one side of the wallet showing the fold for cards or the like open.

Fig. 4 is a front view of the other side of the wallet showing the billfold open.

Fig. 5 is a perspective view showing the wallet in another position, with the billfold unsnapped.

Fig. 6 is a view showing the greater part of the different sheets of material from which the wallet is formed laid side by side.

Fig. 7 is a section on the line 7—7 of Fig. 5.

Fig. 8 is a view showing one end wall of the coin pocket before it is secured in the wallet.

Fig. 9 is a perspective view similar to Fig. 1 showing a wallet constructed in accordance with a modification of this invention.

Fig. 10 is a view showing the elements of Fig. 6 in assembled form.

The wallet, according to this invention, comprises a center coin pocket 10 having two end walls or gussets 11 and closed by a "zipper" 12 extending along the length of the pocket and

2

down one side thereof over the adjacent end wall, the "zipper" thus having two portions at right angles to each other. On one side of the coin pocket is a billfold 13 having two compartments 14 and 15 for receiving bills, checks or the like. At the other side of the coin pocket is a fold 16 having two compartments 17 and 18 for receiving identification cards, licenses and other papers, compartments 17 and 18 having transparent windows 19 and 20 respectively. The billfold is held closed by a snap fastener 21 and the other fold is held closed by a snap fastener 22.

The construction of the wallet is unique. Most of the sheets of material from which the wallet 15 is formed are shown in Fig. 6 laid out side by side in the fashion in which they are disposed in the finished wallet. Starting at the right side of Fig. 6, the first sheet 23 forms the frame for the two windows of the fold 16, sheet 23 having two openings 24 and 25 and a slot 26 therebetween. Sheet 23 may be of leather. The two parts of snap fastener 22 are secured to the top and bottom of sheet 23. Windows 19 and 20, which are sheets of Celluloid or transparent plastic, come next and in the wallet are glued to the sheet 23 over the openings thereof.

A sheet of cloth 27 extending the full length of sheet 23 for lining the two compartments of the card fold, comes next. Thus it will be seen that

30 sheet 23 serves for both compartments of the card fold, the slot 26 forming the opening into both compartments, and both compartments are lined by a single sheet of material.

After the sheet 27 come two sheets of leather 35 28 and 29, each bent U-shaped and each opening outwardly so that their inner U-bend ends are adjacent each other in line with the slot 26. Sheet 28 forms an outer surface of the wallet, one portion 28' forming the back of the flap for

40 the card fold and the other portion 28'' forming part of the back for the bill fold. The sheet 29 forms the inside of the coin pocket. The end walls 11, a gusset sheet from which they are formed being shown in Fig. 8, will be secured to

45 the side edges of the sheet 29 to form the ends of the coin pocket and the slide fastener 12 will be secured to the inturned outer edges and to one pair of inturned side edges.

In the closed wallet the billfold does not extend the full height of the wallet, as is clearly shown in Fig. 1. Therefore a short sheet of leather 30 is provided adjacent the sheet 29. Next come the sheets of material that form the two compartments of the bill fold. First comes a narrow sheet of leather 31 having one edge even with

the inner edge of sheet 30 and extending therefrom to form the end of the billfold. Then come alternate sheets of cloth and leather 32 to 37 respectively, the relative widths of these sheets being well shown in Fig. 7. The snap fastener 21 has two parts, one of which is in sheet 31 and the other portion of which is in sheet 37, these fastener parts extending through sheets 32, 34 and 36.

Some of the sheets extend around the edges of other sheets to bind them and are secured thereto by sewing. For instance, sheet 28 extends around the edges of the adjacent sheets 23 and 27 and is sewn thereto as at 28a. The same is true of sheets 30 and 31. The portion of sheet 23 adjacent the coin pocket also extends around the adjacent inturned edges of 29 for binding. There remains to be bound only the middle portion of the billfold and this is bound by two separate narrow strips of leather 38. Sheets 33, 35 and 37 are also folded over the adjacent sheets of cloth 32, 34, and 36 to bind them, as is clearly shown in Fig. 7 and the outer edges of end walls 11 are turned over to bind them as is shown in Fig. 8.

An important feature of the present invention, over and above the features set forth in the foregoing description, is that the coin pocket is closed by a "zipper" than runs along the longitudinal edge and one of the edges at right angles thereto, thereby covering an end wall. This provides the simplest and most economical possible manner of closing the coin pocket against any possible loss, because when the wallet is placed in a pocket with the closed side up, coins cannot possibly be lost out of the coin pocket, as the side and bottom of the pocket will positively be closed by the "zipper." The top is then closed only by the end wall and not by the "zipper." If the coin pocket were completely closed by the "zipper" a longer slide fastener would be employed, unnecessarily adding materially to the cost of the wallet. If only the longitudinal edge of the coin pocket was closed by a "zipper", then coins might be lost out of the end that was disposed at the bottom end of the wallet when the wallet was disposed in a pocket.

A modified wallet is shown in Fig. 9 which is just like the wallet of Fig. 1 except that the card fold is eliminated, only the bill fold and coin pocket being present. In this construction, a portion 39 which corresponds to portion 28, Fig. 6, is secured to the adjacent portion of sheet 29' to form one outer face of the wallet. Other parts of the wallet of Fig. 9 corresponding to similar parts of the wallet of Fig. 1 are indicated by like reference characters with an accent added and no further description thereof is deemed necessary.

Having thus described my invention, what I

claim as new, and desire to secure by United States Letters Patent is:

1. A wallet comprising a sheet of material folded to form a coin receptacle presenting opposite sides and a bottom, an outer sheet attached at its mid-portion to the bottom of said coin receptacle and presenting free opposite ends, a card pocket member attached to one side of said coin receptacle and to a side of one of said free ends and having a central opening for card withdrawal from two sides at its center fold, a billfold member secured at its mid-portion to the opposite side of said coin receptacle from said card pocket member and having one end secured to the end of said outer sheet opposite the end thereof to which said card pocket member is attached, and the other unattached end of said billfold member constituting a closure flap for the bill fold.

2. A wallet comprising a sheet of material folded to form a coin receptacle presenting opposite sides and a bottom, an outer sheet attached at its mid-portion to the bottom of said coin receptacle and presenting free opposite ends, a card pocket member attached to one side of said coin receptacle and to a side of one of said free ends and having a central opening for card withdrawal from two sides at its center fold, a bill fold member secured at its mid-portion to the opposite side of said coin receptacle from said card pocket member and having one end secured to the end of said outer sheet opposite the end thereof to which said card pocket member is attached, the other unattached end of said bill fold member constituting a closure flap for the bill fold, the end of the outer sheet to which the card pocket member is attached constituting a closure flap for the card pocket and means for detachably holding said closure flaps closed.

SAMUEL PLOTZKY.
